[57] CLAIM

The ornamental design for a bottle, as shown and described.

DESCRIPTION

FIG. 1 is a perspective view of a bottle showing a first embodiment of my new design;

FIG. 2 is a front elevational view of the bottle of FIG. 1;

FIG. 3 is a side elevational view of the bottle of FIG. 1, the opposite side being a mirror image thereof;

FIG. 4 is a back elevational view of the bottle of FIG. 1;

FIG. 5 is a bottom plan view of the bottle of FIG. 1;

FIG. 6 is a top plan view of the bottle of FIG. 1;

FIG. 7 is a perspective view of a bottle showing a second embodiment of my new design;

FIG. 8 is a front elevational view of the bottle of FIG. 7;

FIG. 9 is a side elevational view of the bottle of FIG. 7, the opposite side being a mirror image thereof;

FIG. 10 is a back elevational view of the bottle of FIG. 7;

FIG. 11 is a bottom plan view of the bottle of FIG. 7; and,

FIG. 12 is a top plan view of the bottle of FIG. 7.
